UNITED STATES PATENT OFFICE

ROBERT GOOD, OF WASHINGTON, PENNSYLVANIA, ASSIGNOR TO HAZEL-ATLAS GLASS CO., OF WHEELING, WEST VIRGINIA, A CORPORATION OF WEST VIRGINIA

METHOD AND APPARATUS FOR ANNEALING GLASSWARE

Application filed April 28, 1924. Serial No. 709,595.

The invention relates generally to a new and improved method and apparatus for annealing glassware, and consists of a vertical, or substantially vertical, tubular construction through which the glassware slowly travels from top to bottom, the glassware being gradually cooled during its passage.

The objects and advantages of the invention will be fully set forth in the following detailed description, and the construction of the leer will be clearly understood by those skilled in the art when said detailed description is considered in connection with the accompanying drawings, in which:

15 Figure 1 is a vertical section through one of the tubular ovens, and showing an endless conveyer associated therewith, the structure being broken away in two places on account of its length.

20 Figure 2 is a plan view of the leer.

Figure 3 is a detail view illustrating a shutter construction for closing the bottom of the leer.

Figure 4 is a vertical sectional view of a modified construction; the conveyer outside of the leer, and the operating mechanism therefor being omitted, and

25 Figure 5 is a fragmentary horizontal sectional view of the modified form of leer, the section being taken on line 5—5 of Figure 4.

Referring to the drawings more in detail, particularly to Figures 1, 2 and 3, numeral 1 indicates a muffle or oven, the passage through which is preferably cylindrical, as indicated by numeral 2. The muffle may be manufactured of any desired material, such as carbofrax, and in the preferred construction these carbofrax blocks will be of the shape indicated in Figure 2; i. e., each block 35 will be provided with a semi-cylindrical passage adapted to align with a similar passage in the adjacent block, thereby forming a cylindrical passage when the blocks are assembled.

40 Also provided in each of the muffle blocks is a burner passage 3 shown in plan in Figure 2, and arranged in this passage is a burner 4 comprising a tube provided with a plurality of jet holes. I have illustrated two of these burners, but any number may be em-

ployed, and by the selective use of them the effective length of the muffle may be varied. Any suitable means may be provided for furnishing air to the burners, such as passages communicating with the atmosphere and having control dampers 5.

The length of the muffle will vary in accordance with the height of the ware and the speed with which the articles are carried therethrough, although it will be understood that the length may be varied within very wide limits, as conditions warrant. And in place of actually varying the length of the muffle, the effective length thereof may be varied as above described. Arranged below the muffle is another tubular member of heat-absorbing material, such as ordinary fire-clay, or other refractory material, as indicated by numeral 6. This heat-absorbing member becomes saturated with heat, furnishing substantially a fireless extension of the muffle, and its length also is governed by the height of the ware and the speed with which the articles are carried therethrough. While I have specifically described this section of the leer as formed of heat-absorbing material, it will be understood that the invention is in no manner limited to a leer having the heat-absorbing section, and in place of the heat-absorbing material I may employ any desired non-heat-absorbing material.

70 Arranged below the heat-absorbing member is a sheet metal member 7 which extends all the way from the bottom of the heat-absorbing member 6 to the bottom of the leer, which may be ten or fifteen feet, or any length desired.

75 Any number of these tubular annealing ovens or leers may be arranged in a series; and in the particular construction illustrated herein I have shown three of the tubular leers arranged side by side. This battery of ovens is inclosed in a casing of insulating material, such as sil-o-cel, as indicated by numeral 8.

80 Provided in the casing of insulating material is a passage 9 extending from the top to bottom of the construction, there being one of these passages for each leer, and arranged within this passage is one run of an endless

chain or belt 10. The endless chain passes over an idler at the bottom of the leer and over a driving sprocket 11 at the top of the leer. Obviously, the sprocket may be driven intermittently by a motor or any other driving means; but I have illustrated herein merely a hand crank 12 for rotating a worm 13 engaging a worm wheel 14 fixed on the sprocket shaft.

10 A number of flights or shelves 15 are attached to the endless chain at regular intervals, and these shelves project into the tubular oven through a slot 16 extending from the top to the bottom of the oven. Attached to each of the flights is a relatively narrow plate 17, and these plates pass down through the passage 9 and cover the slot 16. An inspection of Figure 1 will show that the ends of adjacent plates are oppositely beveled so that they will overlap, thereby constituting means for preventing the entrance and exit of air to and from the leer through the slot 16. While I have illustrated the plates with oppositely beveled ends, it will be understood that any overlapping construction of the plates may be employed. These plates 17 possess the further function of bracing and adding rigidity to the conveyer flights.

30 The bottom of each of the tubular ovens and the bottom of each of the passages 9 are provided with a pair of tiltable closure members 18, which extend entirely across the bottom of each leer and passage 9, and which are normally held in closed position by means 35 of counterweights 19, thereby preventing to a large extent the entrance of air to the leer. The specific structure here described does not form an essential feature of the invention, and obviously any means for accomplishing 40 the same purpose may be employed.

Positioned below the leer is a chute 20 into which the glassware falls after having been annealed, and it is delivered by the chute to an endless belt 21 which conveys the ware to 45 any desired point.

The operation of the apparatus will now be described.

At the completion of the manufacturing process the articles, while still retaining their 50 residual heat, are placed on the endless conveyer by an attendant or by automatic machinery. It will be understood, of course, that if the residual heat is not sufficient for the annealing operation, such additional heat as 55 may be necessary will be furnished in the muffle. It is found that very little, if any, additional heat will be necessary, as will appear hereafter. As each article is placed on a conveyer shelf the endless conveyer is 60 moved one step to carry the articles within the muffle. This operation is continued step by step until the articles are carried the full length of the leer and are delivered through the chute 20 to the conveyer 21.

65 Each hot article that is placed in the leer

has beneath it another article at only a slightly lower temperature than itself, and the heat that is radiated from this lower body functions as a baffle or barrier to prevent the rapid radiation of heat from the upper article. While 70 I have simply mentioned the article directly beneath the article last introduced, it will be obvious that there is a whole series of articles below the uppermost article, and each one of these series functions in the same manner to reduce radiation from the uppermost article, though, of course, the articles further removed from the uppermost article do not exert this influence to the same extent as does the article immediately beneath it. It 75 will also be understood, of course, that while all of the heated articles below the uppermost article tend to prevent radiation of heat from that article, so, too, is radiation of heat from lower articles retarded by the articles 80 below them which have a temperature only slightly lower.

It will also be understood that as the articles are introduced at the top of the leer in a heated condition and slowly move downwardly through the chamber, after passing through the muffle, the contents of the chamber will give up their heat gradually as they move down and the air thus heated will rise to the top of the leer, thereby contributing to 95 the maintenance of the temperature of the upper portion of the chamber.

In order to properly anneal glassware, the articles should be gradually cooled from about 950° to about 600°; and from the foregoing description it will be apparent that the temperature of the leer disclosed herein will naturally be the highest at the top of the leer, and that this temperature will be decreased very gradually toward the bottom of 105 the leer.

It is also thus apparent that in annealing glassware in the manner described herein very little, if any, heat other than the residual heat of the articles is necessary. If the 110 articles were introduced at the bottom of the leer and were carried upward, the heat given off by the articles would rise to the top of the leer and consequently the articles would be discharged from the leer at substantially 115 the same temperature at which they entered. And it is also true that if a horizontal leer were employed the operation would be by no means the same, for there would not be the same even distribution of heat at a gradually 120 lowering temperature; and, further, it would be necessary to supply a large amount of heat to the leer, for the horizontal leer does not present the same economical arrangement as this vertical leer wherein the heat given off by the articles being annealed rises to the top to contribute to the maintenance of the temperature of the upper portion of the leer.

The apparatus disclosed in Figures 4 and 125 5 is similar in substantially all respects to the 130

apparatus hereinbefore described, with the exception that in this modified form I have eliminated the burners and depend solely on the residual heat of the articles to furnish sufficient heat to accomplish the annealing 5 operation. As no additional heat is employed in this modified construction, I eliminate the muffle and employ a tubular member 22 of heat-absorbing material, such as an ordinary fire-clay or other refractories 10 commonly used, and which may be of any desired length; and below this said chamber is arranged a sheet metal member 7, the same as disclosed in Figure 1. By reference to Figure 15 it will be seen that the heat-absorbing blocks 22 are constructed and arranged in the same manner as the muffle blocks shown in Figure 2, the only difference being that no passages are provided for burners.

It is believed to be entirely unnecessary to 20 describe the operation of this modified form of leer, for its operation will be clearly understood from the description of the operation of the leer disclosed in Figure 1. In that previous description it was shown how each 25 of the lower articles being annealed tended to prevent the radiation of heat from the upper articles, and that the air that was heated by the radiation of heat from the 30 articles rose to the upper portion of the leer to maintain the temperature of that part of the leer. And the purpose of the modified 35 form of leer is to use this heat to the fullest extent, thereby avoiding the requirement of any additional heat.

In accordance with the patent statutes, I 40 have described what I now believe to be the best embodiment of the invention, but I do not wish to be understood whereby as limiting myself or the scope of the invention, as 45 many changes and modifications may be made without departing from the spirit of the invention; all such I aim to include in the scope of the appended claims.

Having thus described the invention, what 45 I claim as new and desire to secure by Letters Patent is:

1. The method of annealing glassware which consists in placing the glassware while 50 in a heated condition in the top of the leer, utilizing the residual heat of the articles as the sole source of heat for the annealing operation, utilizing the heat of the lower articles to retard the radiation of the heat of the 55 upper articles, and carrying the articles through the leer from the top to the bottom thereof.

2. Means for annealing glassware, including 60 a substantially vertically arranged leer, a portion of the leer being lined with heat-absorbing material, said leer being inclosed in a casing of insulating material, and a conveyer for carrying the glassware through the 65 leer from top to bottom thereof, only one run

of said conveyer being arranged within the leer.

3. Means for annealing glassware, including a substantially vertically arranged leer, a conveyer for carrying glassware through 70 said leer from the top to bottom thereof, said conveyer provided with spaced shelves for supporting the glassware, said shelves constructed to conform substantially to the cross sectional size and shape of the leer, 75 thereby constituting means tending to retard the passage of the heated air through the leer.

4. Means for annealing glassware, including a substantially vertically arranged leer, 80 a conveyer for carrying glassware through said leer from top to bottom thereof, said conveyer provided with spaced shelves for supporting the glassware, said leer being substantially cylindrical in shape and said shelves 85 substantially conforming in size and shape to the cross section of the leer, thereby constituting means tending to retard the passage of the heated air through the leer.

5. In a vertical leer for annealing glassware, an endless chain, and leer pans rigidly attached to said chain, said leer pans mounted to extend substantially horizontally from the chain while in the leer, whereby the leer pans may be closely arranged, and said leer pans 95 substantially conforming in size and shape to the cross section of the leer.

6. A leer for annealing glassware, including a substantially vertically arranged oven, a casing of insulation material inclosing the 100 oven, said casing having a passage therethrough, said oven and passage communicating through the medium of a continuous slot, an endless chain having one run thereof positioned in said passage, spaced arms carried by the endless chain and projecting through the slot into the oven, and shelves carried by the arms. 105

7. A leer for annealing glassware, including a substantially vertically arranged oven, 110 a casing of insulation material inclosing the oven, said casing having a passage therethrough, said oven and passage communicating through the medium of a continuous slot, an endless chain arranged to travel through 115 the passage, spaced arms carried by the endless chain and projecting through the slot into the oven, shelves carried by the arms, and plates carried by the endless chain and arranged to close said slot.

8. A leer for annealing glassware, including a substantially vertically arranged oven, a casing of insulation material inclosing the oven, said casing having a passage therethrough, said oven and passage communicating through the medium of a continuous slot, an endless chain arranged to travel through 125 the passage, spaced arms carried by the endless chain and projecting through the slot into the oven, shelves carried by the arms, 130

and plates carried by the endless chain and arranged to close said slot, said plates having an end-to-end overlapping relation when in operative position.

5 9. Means for annealing glassware, including a substantially vertically arranged leer, a conveyer for carrying glassware through the leer from top to bottom thereof, and means arranged at the bottom of the leer to 10 prevent the admission of air thereto between the discharging intervals.

10 10. Means for annealing glassware, including a substantially vertically arranged leer, a conveyer for carrying glassware through 15 the leer from top to bottom thereof, and pivotally mounted doors for closing the bottom of the leer.

11. Means for annealing glassware, including a substantially vertically arranged leer, 20 a muffle forming the upper portion of the leer, a heat-absorbing member forming a portion of the leer below the muffle, and means for carrying glassware slowly through the leer from top to bottom thereof.

25 12. Means for annealing glassware, including a substantially vertically arranged leer, a muffle forming the upper portion of the leer, a heat-absorbing member forming a portion of the leer below the muffle, a member 30 forming a continuation of the leer below the heat-absorbing member, and means for carrying glassware slowly through the leer from top to bottom thereof.

13. Means for annealing glassware, including 35 a substantially vertically arranged leer, a muffle forming the upper portion of the leer, a heat-absorbing member forming a portion of the leer below the muffle, a member forming a continuation of the leer below 40 the heat-absorbing member, a conveyer for carrying glassware through the leer from top to bottom thereof, and means arranged at the bottom of the leer to prevent admission of air thereto between the discharging intervals, 45 said leer being inclosed in a casing of insulation material.

ROBERT GOOD.
